CATALYTIC APPARATUS

Koloman Roka, Konstanz, Germany, assignor, by
mesme assignments, to the firm Deutsche
Gold- und Silber-Scheideanstalt vormals
Roessler, Frankfort-on-the-Main, Germany, a
corporation of Germany

Application November 11, 1929, Serial No. 406,437,
and in Germany November 28, 1928

5 Claims. (Cl. 23—288)

In carrying out catalytic gas reactions which take place with the addition or evolution of heat care is taken to lead the gases or the gas and vapour mixtures through pipes packed with the 5 catalyst, cooled externally for example by air or heated by hot gases. The increase in the cross section and consequently the capability of such catalyst pipe to allow the gases to pass are placed within extremely narrow limits owing to the fact that with increasing diameter of the pipes 10 the exchange of heat between the separate portions of the catalyst material and the outer wall becomes increasingly less effective. It is, therefore, necessary, when working with large amounts 15 of gas, to employ a correspondingly large number of pipes individually of relatively small diameter, but connected up in parallel.

It has been found that catalytic gas reactions, in particular such reactions as require an 20 exact maintenance of definite temperatures to a particularly high degree, or such reactions which owing to specially great absorption or evolution of heat require a specially energetic action of the cooling or heating means, can be 25 carried out considerably better and with greater certainty in reaction vessels of such a flat shape that their inner space is mainly bounded by two surfaces parallel with one another or substantially parallel, the distance between which is 30 small relatively to the other dimensions of the container so that the distance of the catalyst from the container wall does not exceed at any place the limits within which a sufficiently rapid heat exchange is possible, with the result that 35 the containers so obtained, for example of pocket shape, are moreover so formed that the catalyst may be easily introduced and removed, and at the same time a good distribution of the entering gas over the whole cross section of the catalyst is ensured.

With such containers, on account of the large containing space of the individual containers, which may amount to about 100 litres, the further advantage is obtained in contrast with sets 45 of pipes of corresponding capacity, that the catalyst can be filled into the containers and removed from the same very much more quickly owing to the smaller number of filling and emptying openings and that furthermore any 50 small irregularities in the thickness of the filling are very easily compensated over the whole cross section of the container while with a set of pipes the resistance to the passage of the gases is never the same in each of the separate pipes, 55 with the result that the gases in such cases

will flow through the pipes of lower resistance in larger amounts than through those with greater resistance. Consequently for example in exothermic reactions, the action of the external cooling medium in pipes of lower resistance, which naturally depends only on the surface of the pipe, will be substantially smaller than in the other pipes which impose a greater resistance to the gas, and through which smaller amounts of gas flow. The result of all these 60 irregularities is, that considerable differences in the internal temperature arise, which in some cases may exceed considerably the upper and lower temperature limits permissible for the 65 action.

The same is the case in the converse direction with endothermic reactions in which the desired 70 reaction temperatures must be produced by uniform supply of external heat.

These drawbacks naturally are the more serious 75 in proportion to the narrowness of the temperature limits for the gas reactions to be carried out or to the amounts of heat to be supplied or withdrawn, the result being that on the one hand not only incomplete conversion takes place in the cold 80 pipes, and on the other hand the formation of decomposition products in the parts of the catalysts which are too hot, but also the catalyst is 85 injured by overheating.

By employing containers according to the invention 90 the said drawbacks are largely avoided, and owing to the uniform flow of the gases through these containers it is possible to use them in larger numbers connected in parallel, because the relative differences in the capacity of the individual 95 containers to allow the flow of gas becomes much smaller than between the individual small units when pipes are used.

A further advantage in contrast with such pipes 100 is the avoidance of numerous connecting members, and of the corresponding number of points at which there are packed joints which easily give rise to losses of gas.

The described method of working has proved 105 to be of particular advantage in the production of ketones, especially acetone from acetylene, alcohols, esters, aldehydes or other bodies capable of forming ketones by the treatment of these bodies with steam at high temperatures, for example temperatures between 250° and 650° C., in the presence of suitable catalysts, especially oxygen compounds of metals as for example oxides of iron or other oxygen compounds of heavy metals or mixtures of such compounds or of oxygen compounds of heavy metals with such compounds of 110

- light metals in the presence or absence of metals, which latter when present preferably serve as the carrier for the oxygen compounds of metals, preferably in intimate contact therewith.
- 5 It has been found that in an oven assembly with pocket shaped reaction vessels for example constructed in the manner described hereinafter, all these reactions, whether they take place exothermically, endothermically or without substantially sensible heat effects, may be carried out in a particularly favorable manner and with a substantially decreased oven space and correspondingly simplified oven construction as contrasted with a set of pipes.
- 10 15 It is also possible without further steps to use one and the same oven assembly for example for the endothermic formation of ketones from alcohol, and also for the exothermic formation of ketones from acetylene.
- 20 25 The production of hydrogen from water gas as well as hydrogenation and dehydrogenation processes may be mentioned as further examples of reactions which may be carried out with great advantage in assemblies of reaction vessels of the kind described. The production of hydrogen takes place according to the equation:
- $$CO + H_2O \rightleftharpoons H_2 + CO_2 + 10 \text{ kilocalories.}$$
- In order to have as complete as possible a conversion it is, as is known, important to keep the reaction temperature as low as possible, since it is only at low temperatures that the balance lies sufficiently on the hydrogen side. This again requires the use of specially active catalysts, that is to say, catalysts which make possible a sufficient speed of reaction at low temperatures, and these again are sensitive in regard to high temperatures which may occur temporarily if the heat of reaction is insufficiently led away. The sharp temperature regulation necessarily following from these considerations is easily made possible when carrying out the reaction according to the present invention.
- 40 45 While in the production of hydrogen the evolution of heat is not in itself too great and is partly taken up also by the steam which is present in excess, this is not the case in hydrogenation processes in which about 20 kilocalories are set free per molecule of the hydrogen obtained. On the other hand, in these reactions, the catalysts employed (such as nickel or copper reduced with special precautions, and on suitable carriers) are very specially sensitive to overheating so that if the heat is not removed sufficiently rapidly these catalysts become very quickly inactive.
- 50 55 It is known for example that for these reasons it is difficult to hydrogenate acetaldehyde on a technical scale to form ethyl alcohol. This state of affairs is still more marked for example in the production of butyl alcohol from croton aldehyde in which for each molecule of butyl alcohol two molecules of hydrogen must be formed with the release of about 40 kilocalories. It has been found that these reactions also can be carried out with great advantage in pocket shaped reaction vessels according to the invention.
- 60 65 It has been found further that in carrying out such catalytic gas reactions, for example the above-mentioned production of ketones, the preheating and prepurification of the gases, vapours or gas-vapours mixtures to be supplied to the reaction vessels, may be carried out with good results in vessels of the same kind, for example the pre-heating may be carried out in a very uniform and well controlled manner in such vessels which are
- filled with a material of good heat conductivity and sufficient heat capacity, as for example scrap iron or other metallic bodies. Similarly, gases or vapours or gas-vapour mixtures from which tarry or other materials injurious to the catalyst may separate out at the commencement of heating, may be purified by passing them through pocket shaped containers according to the invention which are packed for example with coke or another suitable filling material, before passing them through the main reaction vessels.
- 80 85 In this case also the purification occurs specially easily and thoroughly in consequence of the co-operation of the good temperature regulation and the uniform subdivision of the gas currents both over the cross section of the individual reaction vessels and over a plurality of such vessels connected in parallel.
- 90 95 A number of embodiments of reaction vessels suitable for use in carrying out the method of working described are illustrated in the annexed drawings wherein:
- 95 100 Figure 1 is an elevation of such a vessel from the side.
- 100 105 Figure 2 is a central longitudinal section of the same on the line A—B of Figure 1, while Figure 3 is a cross section on the line C—D of Figure 1, and
- 105 110 Figure 4 is a perspective view of a number of such vessels connected in parallel.
- 110 115 In these drawings 1 and 2 indicate the parallel side walls which bound the greater part of the inner space of the container, and which are spaced a small distance apart relatively to the other dimensions of the vessel, which is provided on its outer surface wholly or partly with ribs 3 or similar members. 4 and 5 are end tubes for filling in and removing the catalyst or other filling material and for supplying and taking off gases, they are preferably located between the side walls 1 and 2 at opposite ends of the container so that the change in cross section of the vessel from that of the tubes 4, 5, conveniently of the same diameter as the relative distance apart of the walls 1 and 2, is effected by the oblique surfaces 6 to 9.
- 115 120 These tubes are conveniently provided with lateral subsidiary flanged openings 10 and 11 which for example serve for supplying and taking off the gas and by means of which also a number 125 of such containers may be connected in common to connecting pipes in the case of the parallel connection shown in Figure 4. The vessels in some instances may be built without ribs. Tubes 4 and 5 not employed for connecting purposes, but 130 only for filling or emptying purposes could be closed in any suitable manner for example as is shown in Figure 1 in connection with the tube 4 by means of a clamp closure 12 together with a cover 13 or in any other manner.
- 130 135 The filling and the removal of the catalyst or other filling bodies is substantially facilitated by the uniform narrowing of the cross section of the vessel for example by the inclined end walls 6 to 9 towards the inlet and outlet openings, and, moreover, a uniform distribution is ensured for the gas inlet and outlet over the whole cross section of the vessel. The union tubes mounted at the ends of the vessel preferably have a diameter which is equal to the distance between the main boundary walls 1 and 2 of the vessel. One of the openings of the vessel, for example the upper opening, serves for filling in the catalyst and the other for removing the same. This takes place very easily and quickly, including any par-

ticles adhering to the walls of the vessel, since these can be easily moved from the filling unions and all these operations are also easily carried out with the vessels built into the furnace.

5 The clear distance between the two main surfaces 1 and 2 of the reaction vessel must not exceed 200 millimeters in general. The width of the vessel is limited by the necessity of being able to distribute the catalyst from the filling opening over the whole cross section of the vessel. The width will generally lie between 500 and 1000 millimeters. The height of the pocket shaped unit depends upon the details of the reaction to be carried out. If it is carried out conveniently 10 in relatively thin layers of catalyst the pocket shaped reaction vessel is relatively short. On the other hand if it is a question for example of a reaction which proceeds slowly and which requires a large volume of catalyst, long pockets 15 are preferably selected up to a length of 2000 millimeters and more. In a similar fashion the ratio between the width and length of the pocket is always adapted to the existing special working conditions.

20 25 The vessels according to the invention are with advantage provided on their outer surface with ribs, as shown at 3 in the drawings, which increase the surface of the pocket giving out or absorbing heat with respect to the heating or cooling medium, for example warm or cold gases, 30 as well as conducting these gases in the desired paths.

The preliminary treatment of the gases in apparatus of this kind has essential working advantages because the control of a unit comprising apparatus of the same construction is much simpler and a preheating of the reaction gases is simultaneously attained with the preliminary treatment.

40 45 The shape of the reaction vessels may naturally be varied within wide limits without departing from the scope of the present invention. For example, the main boundary walls 1, 2 instead of being made flat as shown could be made of other shapes, for example of wave shape whilst still being a substantially constant distance apart, and if desired could be provided internally with ribs arranged in any suitable manner whatever, or the vessel may be made 50 round on its narrow sides and so forth.

55 60 In a similar way the reduction of cross-section of the vessel from the main part to the ends where according to the drawings the filling and emptying tubes are mounted, instead of being effected by oblique surfaces, could be effected by any other suitable guiding surfaces whatever. Also instead of providing a tube at each end of the vessel two or more of such tubes may be mounted at one or both ends, and, moreover tubes may 65 be provided at other parts of the vessel, for example for the purpose of introducing and leading off the reaction gases, for example in such a way that the supply of the reaction gases may take place through a tube mounted half way along the vessel, for example in the middle of one of the boundary surfaces from one or both sides of the vessel, and the gases may be taken off at the ends of the vessel or conversely.

70 75 According to the invention a large number of such vessels may be connected in series with one another as well as in parallel. The parallel connection, as shown in Figure 4, may be conveniently effected, for example, by connecting the lateral auxiliary unions of the necessary numbers of vessels at one and the same end to a cor-

responding number of tubes provided on cross pipes, so that upon passing from one set of vessels to the next connected behind it, only one connecting bend, or in the case of a very large number of pockets two, are necessary.

80 The advantages of the above-described method of connecting together a series of vessels in parallel by means of cross connections arises particularly in the above described method of working if the gases are passed, before their introduction into the reaction vessel proper packed with catalyst, through vessels of the same kind packed with suitable filling bodies with the object, for example, of preheating or separating injurious constituents, since for connecting the parallel series of vessels only one or at the most two pipes are necessary, so that without using a large number of pipe connections the distribution of temperature afforded by the furnace heating can be utilized in the manner most favorable for carrying out the process by employing the desired form of connection.

85 90 The connection of the vessels in series is preferably arranged so that the reaction gases in the first vessel for example are allowed to flow from the top towards the bottom in the second, from the bottom towards the top and so forth, with the result that the length of the necessary pipe connections is very much reduced. As a result it is not necessary to connect the vessels in the 100 series sequence according to their position in space, but they may be connected in another sequence according to the kind of furnace heating, the necessary temperature and amounts of heat and the like, and thus frequently a devious 105 flow of the gases, in which individual vessels or groups of vessels are passed over, proves to be preferable. By assembling together pockets connected in parallel, it is possible with the help of cross pipes to connect together in any desired 110 series sequence with a minimum amount of connecting pipes the vessels of the assemblies increased by the parallel connection.

115 120 In order to produce a particularly uniform temperature or a particularly conveniently graded temperature distribution, this particular method of connection, for example that in which the gas passes first from the first parallel connected series of pockets into the last i. e. the third and then only passes to the middle series, 125 may be found of importance.

125 130 If for example the case of an endothermic reaction occurs as is illustrated by the production of acetone from alcohol, wherein, moreover, in consequence of the excess of water vapour fairly large amounts of heat are necessary for the pre-heating, the method of connection may for example with great advantage in certain cases be such that the vapour mixture is first led into the pre-heating pockets which lie in that part of the furnace in which the heating gases are already relatively cooled, and in fact preferably in counter-current to the heating gases, that is to say in such a way that the vapour mixture first passes into the last or coolest pocket, then into the one before that and so on. When in this way the vapour mixture is raised to the temperature at which the reaction commences, the mixture is led into the foremost of the pockets packed with the catalyst proper on which the heating gas first strikes. In this pocket the greater part of the conversion is consequently completed. In order to maintain the reaction temperature the most vigorous supply of heat is required from this foremost pocket. Then the mixture, already 140

135 145 150

converted for the greater part, flows into the second and third pockets now in counter-current with the heating gases corresponding to the smaller heat requirements for completion of the 5 conversion.

If the pockets according to their series sequence in the furnace gases are indicated as 1, 2, 3, 4, 5 and 6 in cases of the kind referred to, the 10 sequence of connection 6, 5, 4, 1, 2, 3, or a similar sequence would be advantageous. Obviously a heat exchanger for exchanging heat between the gas or vapour mixture to be supplied and that flowing away may be provided outside the 15 furnace assembly proper or the heat relations may be regulated in the desired fashion in any other desired manner.

In the case for example of exothermic reactions the connection will be made quite differently according to the amount of heat released 20 during the reaction and according to the insulation of the furnace. The most suitable method of connection can, however, in each case be foretold with a certain probability, and the success is easily confirmed by the result of tests.

25 I claim:—

1. A reaction apparatus for carrying out catalytic reaction with organic gaseous compounds, comprising a plurality of reaction-chambers being substantially filled with powdery or lumpy 30 catalysts or other filling material and having two of their walls substantially parallel to each other and forming between them an elongated zone of a cross section in which the thickness is small relative to the width, said reaction chambers 35 having cylindrical portions at each end, the internal diameters of which are substantially the same as the thickness of said zone and tapered portions situated respectively between the body portion and the adjacent cylindrical portion, 40 said reaction-chambers being disposed with the aforesaid walls of adjacent chambers in register with, spaced apart from and substantially parallel to one another.

45 2. A reaction apparatus for carrying out catalytic reaction with organic gaseous compounds, comprising a plurality of reaction-chambers being substantially filled with powdery or lumpy catalysts or other filling material and having two 50 of their walls substantially parallel to each other and forming between them an elongated zone of a cross section in which the thickness is small relative to the width, said reaction-chambers being disposed with the aforesaid walls of adjacent 55 chambers in register with, spaced apart from

and substantially parallel to one another, and said walls having projecting ribs on their external surfaces.

3. A reaction apparatus for carrying out catalytic reaction with organic gaseous compounds, 80 comprising a plurality of reaction-chambers being substantially filled with powdery or lumpy catalysts or other filling material and having two of their walls substantially parallel to each other and forming between them an elongated zone of a cross section in which the thickness is small relative to the width, said reaction-chambers being disposed with the aforesaid walls of adjacent chambers in register with, spaced apart from and substantially parallel to one another, 85 and said walls having on their external surfaces projecting ribs extending perpendicularly to the length of the reaction-chambers.

4. A reaction apparatus for carrying out catalytic reaction with organic gaseous compounds, 90 comprising a plurality of reaction-chambers being substantially filled with powdery or lumpy catalysts or other filling material and having two of their walls substantially parallel to each other and forming between them an elongated 95 zone of a cross section in which the thickness is small relative to the width, said reaction-chambers being disposed with the aforesaid walls of adjacent chambers in register with, spaced apart from and substantially parallel to one another, 100 and said walls having on their external surfaces projecting ribs extending perpendicularly to the length of the reaction-chambers, the ribs on each wall cooperating with the ribs on the wall opposed thereto to provide flue-passages there- 105 between.

5. A reaction apparatus for carrying out catalytic reaction with organic gaseous compounds, comprising a plurality of reaction-chambers being substantially filled with powdery or lumpy 110 catalysts or other filling material and having two of their walls substantially parallel to each other and forming between them an elongated zone of a cross section in which the thickness is small relative to the width, said reaction-chambers being disposed side-by-side, with their aforesaid 115 walls substantially parallel and provided with projecting ribs, an inlet pipe, an outlet pipe, and pipe connections connecting the openings at one end of the reaction-chambers in common to the 120 inlet pipe and the openings at the other end in common to the outlet pipe.
